UNITED STATES PATENT OFFICE.

HENRY SCHNACKENBERG, OF CRESCO, PENNSYLVANIA.

DRINKING CUP.

Application filed September 10, 1921. Serial No. 499,619.

To all whom it may concern:

Be it known that I, HENRY SCHNACKENBERG, a citizen of the United States, and a resident of Cresco, in the county of Monroe and State of Pennsylvania, have invented a new and Improved Drinking Cup, of which the following is a description.

My invention relates to paper drinking cups and more particularly to a drinking cup in which the bottom is formed by overlapped tongues integral with the cup and bent into position to form a closure of the cup at the bottom.

The general object of my invention is to provide a cup of the indicated character improved in various particulars to the end that the cup will be reinforced at the bottom, the cup being further characterized by a novel arrangement of the tongues constituting the bottom.

Reference is to be had to the accompanying drawings forming a part of this specification, it being understood that the drawings are merely illustrative of practical examples of the invention.

Figure 1 is a vertical section of a drinking cup formed in accordance with my invention, as indicated by the line 1—1, Figure 2;

Figure 2 is a horizontal section on the line 2—2, Figure 1;

Figure 3 is a plan view of the blank that may be utilized for forming the cup and in which the slits dividing the tongues are carried through the reinforcing zone;

Figure 4 is a vertical section of the lower portion of the cup, the cup having the bottom slightly modified as referred to hereinafter;

Figure 5 is a fragmentary view showing a portion of the blank and modified so that the slits separating the tongue terminate at the reinforcing zone instead of extending through said zone.

The body 10 of the cup is made in practice of wax paper as is usual in the trade and in practice the blank, as shown in Figures 3 and 4, from which the cup body is formed is made with a flange 11 at one side terminating short of the bottom of the blank and adapted to overlap the opposite edge when the blank is bent to form a round body. The bottom designated generally by the numeral 12 is elevated above the lower edge of the body so that the latter has an

annular sustaining bottom edge 13 below the bottom.

The bottom 12 is formed of tongues 14 the arrangement of which is illustrated in Figures 3 and 5 in which it will be observed that the tongues are of gradually increasing length from the side edges of the blank to a point 15, said point being formed at the juncture of two adjacent tongues and pronouncedly nearer to one side edge of the blank than to the other. The edge formed jointly by the tongue ends presenting a long curve 16 and a short curve 16^a. The purpose of the described arrangement of the tongues is to produce an approximate uniformity throughout the bottom 12 and prevent accumulated material at the center by reason of too great a plurality of overlapping tongue parts.

In association with the bottom as described, I form the blank 10 with a reinforcing zone 17 scored on two lines 18, 18^a. The slits 19 separating the tongues may extend through the reinforcing zone 17 as in Figure 3 or as shown in Figure 5 the slits 19^a may terminate at the reinforcing zone 17^a making said zone unslit. In forming the cup from the blank the latter is folded on the lines 18, 18^a so that the zone 17 will be upturned at the inner side of the cup below the bottom 12, thereby reinforcing the bottom annularly.

In Figure 2 it will be seen that the reinforcing zone 17 is folded close against the body so that the reinforce flares upwardly in correspondence with the body. In Figure 4 I have shown the modified arrangement in which the upturned zone 17^b is turned up in cylindrical form so as to be spaced from the flaring body 10^a of the cup thereby leaving an annular channel between the reinforcing zone and the body into which the wax may run in the coating of the cup.

In practice the tongues 14 are caused to adhere to each other by the application thereto of a suitable adhesive material which reduces the tongues to a limp condition whereupon by the pressure of a mandrel, the tongues are flattened out into a single plane to form in effect a homogeneous bottom.

I would state in conclusion that while the illustrated example constitutes a practical embodiment of my invention, I do not limit myself strictly to the exact details herein

illustrated, since, manifestly, the same can be considerably varied without departure from the spirit of the invention as defined in the appended claims.

5 Having thus described my invention, I claim:—

1. A drinking cup having the bottom formed of a plurality of tongues overlapping and forming a closure of the cup, there 10 being a reinforcing zone at the base of the tongues and disposed annularly beneath the bottom at the inner side of the body, said zone being spaced from the body to form an annular channel therebetween for receiving wax.
2. A drinking cup formed of a blank and having the bottom formed of a plurality of tongues integral with the body and overlapping to form a closure of the cup, said 20 tongues being of increasing length from the side edges of the cup to a point nearer one side edge than the other.
3. A drinking cup formed of a blank and having the bottom formed of a plurality of 25 tongues integral with the body and overlapping to form a closure of the cup, said tongues being of increasing length from the side edges of the cup to a point nearer one side edge than the other, the ends of the

tongues jointly presenting curves terminating at said point.

4. A drinking cup having the bottom formed with a plurality of tongues overlapping and forming a closure of the cup, said tongues increasing slightly in length 35 from a side edge of the body of the cup toward the opposite edge, the increase in length being more abrupt toward a point short of the opposite side edge.

5. A drinking cup having the bottom 40 formed with a plurality of tongues overlapping and forming a closure of the cup, said tongues increasing slightly in length from a side edge of the body of the cup toward the opposite edge, the increase in length being more abrupt toward a point short of the opposite side edge, and those tongues 45 between the said point and the opposite side edge decreasing in length toward said opposite edge.

6. A drinking cup having a bottom formed with a plurality of tongues overlapping and forming a closure of the cup, said tongues increasing in length from a side edge of the body of the cup to a point short 55 of the opposite edge, the end edges of the tongue being on a curved line.

HENRY SCHNACKENBERG.
